UNITED STATES PATENT OFFICE.

EDWARD McCULIC CORPENING, OF BRIDGEPORT, WEST VIRGINIA.

FENCE.

SPECIFICATION forming part of Letters Patent No. 350,119, dated October 5, 1886.

Application filed May 26, 1886. Serial No. 203,313. (No model.)

To all whom it may concern:

Be it known that I, EDWARD McCULIC CORPENING, a citizen of the United States, residing at Bridgeport, in the county of Harrison and State of West Virginia, have invented a new and useful Improvement in Fences, of which the following is a specification.

My invention relates to improvements in portable fences; and it consists of the peculiar combination and novel construction and arrangement of the various parts for service, substantially as hereinafter fully set forth, and particularly pointed out in the claims.

The object of my present invention is to provide a novel fence which can be easily and readily taken apart without damage to its several parts, so that it can be compactly and snugly folded for storage or transportation, and as quickly and readily put together or constructed by an unskilled person; to provide novel means for connecting the upper ends of the suspending stakes or tripod, which will permit the stakes or legs of the tripod to be readily detached, and which will firmly and rigidly connect the said legs together when they are adjusted for use; to provide novel means for connecting and suspending the ends of the fence rails or panels, which shall prevent them from movement and thereby becoming displaced, and, finally, to improve the fence in minor details, so that it will be very simple, strong, and durable in construction, and cheap and inexpensive of manufacture.

In the accompanying drawings, which illustrate a portable fence embodying my invention, Figure 1 is a side elevation. Fig. 2 is a vertical sectional view on the line *x x* of Fig. 1. Fig. 3 is a side elevation of another form of fence embodying my invention, in which the rails or planks are lapped at their sides. Fig. 4 is a vertical sectional view, corresponding to Fig. 2, of the device shown in Fig. 3; and Fig. 5 is an enlarged perspective view of the connecting device or "union" for the upper ends of the stakes that form the tripod.

Referring to the drawings, in which like letters of reference denote corresponding parts in all the figures, A, B, and C designate the stakes or uprights, which are arranged at an angle to each other to form a tripod, D, which serves to suspend the rails or panels E and the devices for supporting the same, all as pres-

ently described in detail. The upper and lower ends of the stakes or legs of the tripod D are reduced or tapered, the lower ends of the said legs being sharpened, so that they will easily and readily penetrate or enter the ground under the weight of the fence-panels, and the upper ends being only slightly reduced to receive the rings or loops of a connecting device or union, which is shown in detail in Fig. 5. This union F is formed of a single piece of wire, which is first bent or curved to form a loop or ring, *g*, then another loop or ring, *h*, which is arranged to one side of the loop *g*, and is of substantially the same size as the loop *g*, and finally the wire is bent to form a third loop, *i*, which touches the peripheries of the two loops *g* and *h*, and is arranged to one side thereof, the wires crossing or intersecting each other at the points *j*, so as to provide means for suspending a loop for the fence rails or panels, as presently described. After the three loops *g*, *h*, and *i* of the union have been formed from the single piece of wire the free ends thereof are twisted or united together, as shown, and the union may be made at the time of building or constructing the fence; or it may be made before the fence is built by means of suitable formers, over which the wire is passed, and it can then be galvanized to protect it from the action of the weather and increase its durability, so that it can be used a great number of times and will last for a longer period than if made of the wire alone without galvanizing. When the stakes or legs of the tripod are properly adjusted, the rings or loops of the union fit over the reduced upper ends of the same to securely connect the stakes together, and this union is applied to the first stake when it is fitted in the ground during the process of building the fence, and the remaining two stakes are successively fitted in their proper loops, the upper reduced ends of the stakes overlapping or projecting past each other to brace and increase the strength of the tripod at its upper end.

I preferably employ four rails or panels, E, of the fence, although the number can be varied without departing from the principle of my invention; and I will proceed to describe the method by which the rails are suspended and arranged. The rails in the fence-panel shown herein are numbered from 1 to 4, inclusive, as

shown in the first section of the fence, and from 5 to 8, inclusive, in the second section of the fence, and so on throughout the series of sections. The uppermost or top rail, *l*, of the first section of the fence is suspended from the tripod by means of a loop, *G*, which passes through the union at the points of intersection of the loops marked *j*, and depends therefrom for a suitable distance to receive and support one end of the panel *l* of the fence. The end of the rail numbered 2, at the same end of the section, is suspended from the rail *l* by means of a link, *H*, which encompasses the ends of the panels 1 and 2. The end of the panel 3, at the same end of the section, is suspended from the rail or panel 2 in like manner by a link, *I*, and the same end of the panel 4 is also suspended from the rail or panel 3 by a link, *J*. These links are all of suitable length to hold the rails or panels at a suitable distance apart, preferably equidistant from each other, and the loops intermediate of the ends of the panels prevent them from moving vertically, and thereby becoming displaced. The opposite ends of the panels at the tripod of the second section of the fence are suspended in like manner by the loops *G*, *H*, *I*, and *J*, and the end of the panel 5 adjacent to the panels 1 and 2, is fitted or inserted between the ends of said panels 1 and 2, and overlaps the latter. The end of the panel 6 fits between and overlaps the panels 2 and 3. The ends of the panel 7 overlaps the ends of panels 3 and 4, and the end of panel 8 fits beneath and underlaps the lower panel, 4, all as readily seen by reference to Figs. 1 and 2 of the drawings. It will thus be seen that the adjacent or adjoining ends of the panels of two sections of the fence are suspended in a series of loops which are common to the lapped ends of the panels of the said fence-sections, and by means of this peculiar construction and arrangement of the several parts the fence is rendered very simple and cheap to manufacture, and can be rapidly constructed by an unskilled person.

In Figs. 3 and 4 of the drawings I have shown a fence in which a series of boards are substituted for the rails to form the panels, and the meeting ends of the two adjacent sections of the fence are side-lapped instead of over and under lapping the boards, as in Figs. 1 and 2, the relative construction and arrangement of the other parts of the fence being substantially the same; therefore I do not deem it necessary to specifically herein describe the fence shown in the said Figs. 3 and 4.

In building the fence two adjacent tripods are so arranged that the legs *C* thereof are on opposite sides of the fence and in contact with

the rails or panels thereof, and thereby prevent any swaying or swinging movement of the panels under the force thereon of the wind or from other causes; and as a further precaution to prevent swaying of the panel the bottom rails, 4 8, &c., of the fence-sections may be anchored to suitable stakes or other objects in the ground by means of wires or loops *L*, or they may be connected to the legs or stakes of the tripod by similar wires, as will be readily understood.

The operation and method of constructing and removing a fence embodying my invention will be readily understood from the foregoing description, taken in connection with the drawings.

My improved fence is very simple, strong, and durable in construction, can be rapidly constructed and taken apart, and used for any number of times without damage to its several parts, can be easily repaired when broken, or the destroyed parts replaced, and is very cheap of manufacture.

By bending and twisting the ends of the several suspending-loops *G*, *H*, &c., they can be tightened to increase the strain with which they bear on the rails of the fence.

Having thus fully described my invention, what I claim as new, and desire to secure by Letters Patent, is—

1. In a portable fence, the combination of a tripod comprising the diagonal stakes overlapping each other at their upper ends, a union formed of a single piece of wire and having the separate rings or loops which are fitted over the stakes, the fence-panels, and a loop connected with the union and the fence-panels for suspending the latter from the tripod, substantially as described.

2. In a portable fence, the combination of a tripod, a union formed of a single piece of wire and connecting the legs of the tripod, the lapped rails or panels, the loop connected with the union and upper panel, and the loops intermediate of the upper panel and the lower panels, one of the legs of two adjacent tripods being arranged on opposite sides of and in contact with the rails or panels, all arranged and combined substantially as and for the purpose described.

In testimony that I claim the foregoing as my own I have hereto affixed my signature in presence of two witnesses.

EDWARD MCCULIC CORPENING.
